PROPANE DEWAXING OF LUBRICATING OILS

William T. Knox, Jr., Cranford, N. J., assignor to Esso Research and Engineering Company, a corporation of Delaware

Application June 19, 1953, Serial No. 362,735

2 Claims. (Cl. 196—18)

The present invention is generally concerned with the solvent dewaxing of petroleum oil fractions. The invention is more particularly concerned with an improved process for the dewaxing of lubricating oil fractions with a light hydrocarbon solvent, as for example a solvent comprising propane. In accordance with the present process undesirable ice formation is prevented in a solvent dewaxing operation utilizing a solvent such as propane, by employing in conjunction with the propane a relatively small amount of ammonia.

In the refining of hydrocarbon oils such as petroleum oils, it is known to segregate waxes from so-called paraffin distillates, waxy lubes and the like. The segregation of these waxes is secured by a number of processes. For example, it is known to chill the selected wax containing fraction in order to secure crystallization of the wax and to remove the wax crystals from the oil by filtering, centrifuging and the like. It is also known to use various dewaxing solvents such as liquid normally gaseous hydrocarbons, such as propane, as well as other solvents, such as methylethyl ketone and the like. It is also known to utilize in dewaxing operations solvent mixtures wherein one solvent comprises a wax precipitating solvent while the other comprises a solvent having a high solubility for oil. A solvent mixture of this character, for example, comprises 40% by volume of toluene and 60% by volume of methylethyl ketone.

When utilizing a solvent such as propane in a dewaxing operation wherein the stock being treated is subjected to low temperatures, the water present freezes with the resultant plugging of flow lines, valves, sprays, compressor elements and the like. At times the ice freezes in sufficiently large pieces to actually rend the filter cloth. Other disadvantages result due to ice crystals in the system. For instance the presence of ice affects the wax crystallization erratically, resulting in poor filtration rates. The ice crystals may also impregnate the filter cloth giving progressive blinding of the cloth. Furthermore, the icing of instrument lines presents a very real problem since the effectiveness of the operation is controlled by effectively operating instruments. The icing causes these instruments to give poor control to the entire dewaxing operation. In many instances it has been necessary to shut down the plant in order to allow the equipment to be heated so as to melt the ice.

This water enters the system by various paths. It may be present in the feed oil or in the overhead from the steam stripper. Furthermore, since the ice will remain with the wax on the filter cloth, solvent recovered from the wax is segregated as wet solvent. Only the dry solvent recovered from the filtrate can be chilled and used in the heat exchangers. The solvent of course can be dried out but this operation is relatively expensive.

In accordance with the present invention an improved dewaxing process is secured by utilizing in conjunction with the dewaxing solvent an amount of ammonia, less than about 2% by weight preferably less than 1% by

2

weight based upon the total quantity of solvent utilized. The use of ammonia as a freezing point depressant is unique because no other additive can be used which will be effective in such small amounts, and which also can be completely used up. Any excess of the ammonia will be recycled with the solvent. A particularly desirable feature is that ammonia has essentially the same vapor pressure-temperature curve as propane. Therefore, an excess of ammonia may be added and will simply follow the propane through the flash and stripping units.

The process of the present invention may be more fully understood by reference to the drawing illustrating one embodiment of the same.

A waxy feed which comprises a waxy distillate boiling in the lubricating oil boiling range is introduced into the system by means of line 1. In accordance with the present invention a quantity of propane (1-4 volumes of propane per volume of oil) is mixed with the waxy feed by means of line 2. Also, in accordance with the present invention this propane will contain less than 2%, preferably less than 1% of ammonia which is introduced by means of line 3.

The mixture is passed through a heating zone 4 wherein the mixture is raised to a temperature in the range from about 140° F. to 180° F. to secure complete miscibility. The mixture is passed to a cooler 5 in heat exchange with a cooling fluid which is passed counter-currently as illustrated diagrammatically by 6. The cooled mixture is passed into chilling zones 7 and 8 operated alternately. When it is desired to by-pass chilling zone 7 feed line 9 is used.

For the purpose of description, assume that zone 7 is being chilled while zone 8 is being pumped out and the product filtered. Chilling in zone 7 is secured by vaporizing the propane which is removed overhead by means of line 10, compressed in compressor 11 and condensed in cooling zone 12. The condensed propane is recycled by means of line 2. The chilled product at a temperature in the range from about 30° F. to —40° F. is removed from chilling zone 7 by means of line 16 and introduced into a conventional rotary type drum filter 17. This unit comprises a rotary drum containing thereon a filter cloth the lower half of which is submerged in a mass of chilled slurry. The wax collects on the periphery of the drum as it rotates while the filtrate passes through the filter cloth and is removed from the center of the drum by means of line 18. In normal operation ice collects with the wax on the filter cloth. As the drum rotates it is preferably washed with propane through spray element 19 supplied by means of line 20. This washed propane may be removed by a separate line 21 and used as desired.

The wax is removed from the drum with the aid of a scraper element 22 and blowback gas and introduced into a solvent removal zone 23, by means of line 50. Solvent and water are removed overhead from zone 23 by means of line 24 while a solvent-free wax fraction is removed by means of line 25. The lube oil fraction removed by means of line 18 is passed to a distillation zone 26 which comprises two or more distillation stages 26 and 27. Temperature and pressure conditions in zone 26 are adapted to remove overhead by means of line 28 most of the solvent. This is condensed in condenser 29 and recycled in the system. Zone 26 is operated at a pressure in the range from about 175 to 225 lbs. per sq in. gauge. The lubricating oil containing a small amount of propane is removed from zone 26 by means of line 30 and introduced into an atmospheric distillation or stripping zone 27. The final traces of propane are removed from the dewaxed oil by stripping steam which is introduced by means of line 31. The dewaxed oil free

of solvent is removed by means of line 32 while wet propane is removed overhead by means of line 33. The overhead stream is passed through cooler 34 and then into a separation zone 51. The condensed water is removed by means of line 52 while the vaporous propane is compressed by means of compressor 74 and condensed by means of cooler 53. This stream is recycled to the system.

As pointed out heretofore, water present tends to clog up the filter cloth, transfer lines, the spray equipment and the compressors. However, in accordance with the present invention the added ammonia causes the water to form a lower liquid ammoniacal water phase during the chilling cycle. This phase is withdrawn from chiller 7 by means of line 35 and from chiller 8 by means of line 36.

The overhead from zone 23 comprising propane, water and ammonia is passed through cooler 61 and introduced into a settler 42. Propane and ammonia are removed overhead from settler 42 by means of line 63, passed through a compressor 45, a cooler 41 and recycled to the system. An ammonia-water phase is removed from the bottom of settler 42 by line 40 and combined with the water and ammonia removed from chillers 7 and 8 by lines 35 and 36. An ammonia-water phase is also removed from the bottom of settler 51 by means of line 52 and combined with the ammonia-water phases from settler 42 and chillers 7 and 8. This combined stream is passed to distillation zone 37 by means of line 38. Temperature and pressure conditions in zone 37 are adapted to remove overhead by means of line 43 ammonia which is recycled to the system by means of line 3. A water phase is removed from the bottom of zone 37 by means of line 44.

Thus, by the present process all water is removed in

the chilling zone as a liquid ammoniacal water phase which prevents any difficulties due to icing during the latter stages of the process.

When 1% of ammonia is present in propane, equilibrium data show that the water phase will contain about 22% of ammonia. This liquid ammoniacal water phase has a freezing point of -40° F. which is below normal dewaxing temperatures. Since the amount of water present is very small compared with the amount of propane, the ammonia concentration in propane is maintained only slightly higher than equilibrium concentrations.

What is claimed is:

1. In the propane dewaxing of waxy hydrocarbon distillate in the presence of water, the improvement of inhibiting ice formation by said water comprising the steps of adding to a mixture of said waxy hydrocarbon distillate and propane a freezing point depressant consisting essentially of ammonia in the amount of less than about 2% by weight based on the amount of propane present, chilling the mixture so formed to a temperature in the range of from about -30° F. to -40° F., whereby a separate immiscible ammoniacal water phase is formed, separating said immiscible phase from the chilled wax-distillate-propane mixture, and subsequently filtering said chilled mixture to recover precipitated wax.
2. The process according to claim 1 wherein the amount of ammonia used is in the range of from about 0.2 to 1% by weight.
